ROTATING ANTENNA SCANNING SYSTEM

Morris Kline, Little Silver, N. J., assignor to the
United States of America as represented by the
Secretary of War

Application October 25, 1944, Serial No. 560,298

5 Claims. (Cl. 250—33.65)

(Granted under the act of March 3, 1883, as
amended April 30, 1928; 370 O. G. 757)

1

The invention described herein may be manufactured and used by or for the Government for governmental purposes, without the payment to me of any royalty thereon.

My present invention relates to switches, and more particularly, to switches for controlling the flow of high-frequency energy in transmission lines, especially, but not necessarily, in coaxial transmission lines.

While not limited thereto, one application of my present invention is to the control, in a scanning antenna system, of the transfer of energy successively to or from a plurality of antenna elements which are mounted, in advance of a parabolic reflector, for rotation in a vertical or horizontal plane about a central point located along the axis of said reflector. By this arrangement, the direction of radiation or response of the system is periodically shifted through a predetermined angle, at a predetermined rate, to continuously scan a preselected vertical or horizontal sector of space.

It has heretofore been proposed, in order to control the successive transfer of energy in a scanning antenna system of the character above described, to employ brush contact or capacity switches. I have found, however, that the former type of switch sparks at high voltage, and the latter type requires delicate adjustment of the spacing of the plates to obtain proper capacity and still prevent voltage breakdown. Both types are therefore unsatisfactory.

Hence, it is the main object of my present invention to provide a switch which is capable of handling radio-frequency energy at high power levels without the danger of breaking down, and with a minimum loss of such energy.

It is a further object of my present invention to provide a switch, having the above characteristics, which is simple in construction, and easy and economical to fabricate and assemble.

These, and other objects and advantages of my present invention, which will be better understood as the detailed description thereof progresses, are attained in the following manner:

I have found that if two transmission lines, particularly coaxial transmission lines, are separated, at their facing ends, by a gap of somewhat less than about $\frac{1}{4}$ of an inch, one will feed into the other with relatively little loss of energy, and even this loss can be reduced by providing chokes at the facing ends of the lines so that energy is prevented from leaking to the outside thereof. Of course, the lines on both sides of the gap should be matched. I have

further found that the transfer of energy across said gap can be blocked by placing a piece of metal therein. My present invention utilizes these findings by providing said piece of metal in the form of a disc having a sector cut out of the same, and supporting said disc so that when the transmission lines are rotated as a unit, about the axis of the disc, said disc acts as a shutter which intermittently permits communication, across the gap, between the transmission lines.

In the accompanying specification there is described, and in the annexed drawing shown, what is at present considered a preferred embodiment 15 of the switches of my present invention. It is, however, to be clearly understood that my present invention is not limited to said embodiment, inasmuch as changes therein may be made without the exercise of invention and within the 20 true spirit and scope of the claims hereto appended.

In said drawing, the single figure is a perspective view of a scanning antenna system incorporating a switch made in accordance with 25 the principles of my present invention.

Referring now more in detail to the aforesaid preferred embodiment of my present invention, with particular reference to the drawing illustrating the same, the numeral 5 generally designates a transmitting and/or receiving antenna system. Said system includes a parabolic reflector 6 having, for example, an aperture of about 5 feet, and a focal length of about 20 inches. Said system further includes a plurality, here shown as four, of preferably vertically polarized, half-wave dipoles 7, which are mounted, at the ends of parallel-fed, coaxial transmission-line sections 8, for rotation about a central point located along the axis of the reflector 6, approximately 37 inches from the vertex thereof. The outer end of each transmission line section 8 should be such a distance from the axis of rotation thereof that, for about 90° of its rotation, the dipole 7 carried thereby is more or less in the focal plane of the reflector 6. If desired, the transmission-line sections 8 may further be provided with parasitically-excited reflecting elements 9 disposed at an appropriate distance to the rear of the dipoles 7. As will be obvious to those skilled in the art, the plane of rotation of the dipoles, herein shown as vertical, will depend upon whether it is desired to scan in elevation or in azimuth.

The transmission-line sections 8 are preferably L-shaped, and are arranged radially, at an angle

of 90° to each other. The inner ends thereof are supported at the outer ends of radial spider arms 10 which extend from a hub (not shown) mounted upon the shaft 11 of a driving motor 12. The shaft 11 extends through a central, oversized opening 13 formed in a metal disc 14 which constitutes the above-referred to shutter, and at the outer end of said shaft, there is mounted another hub 15, provided with radial spider arms 16 supporting, at their outer ends, additional transmission-line sections 17. The latter constitute parallel-fed branches of a transmission-line slip joint 18, mounted for rotation at the end of a transmission line 19, which may be connected to a radio transmitter or receiver or, through appropriate known circuits, to both a transmitter and a receiver. The transmission-line sections 8 and 17 are so disposed with respect to each other as to present between the aligned ends thereof gaps 20 of somewhat less than about 1/4 of an inch, the facing ends of said transmission-line sections being provided, preferably, with shorted quarter-wave sections 21 so as to prevent radiation by leakage, and thereby hold the loss of energy resulting from the transfer across the gap to a minimum. Furthermore, the line sections 8 and 17 should be matched to each other, and to the equipment at the end of the line 17.

The disc 14, which is supported between the transmission-line sections 8 and 17 in any suitable manner, has a sector cut out of the same, as at 22, the cut-out sector covering about 70° of arc, and being symmetrically disposed about the axis of the parabolic reflector 6, facing said reflector. While the cut-out sector has been described as covering about 70° of arc, it is to be understood that the size of the sector depends on the use to which the switch is being put. In the embodiment under consideration, the switch is being used for lobe shifting, and it has been found that if it is desired to shift the direction of radiation or response of the antenna system through about 45°, symmetrical with respect to the axis of the specific reflector described, 70° is a proper size for said cut-out sector. This is not to be construed as a limitation.

By means of the foregoing arrangement, energy may be transferred between the transmission-line sections 8 and 17 only when the facing inner ends thereof are exposed to each other through the cut-out sector 22 of the disc 14. Now, inasmuch as the disc 14 is fixed, and the transmission-line sections 8 and 17 rotate as a unit, only that dipole whose associated transmission-line sections are momentarily sweeping past the cut-out sector 22 of said disc is effectively connected to the equipment at the ground end of the line 19.

This completes the description of my present invention, and it will be noted from all of the foregoing that I have provided a switch which is capable of handling radio-frequency energy at high power levels, which is simple and inexpensive, and which is amenable to a wide variety of applications and uses.

Other objects and advantages of my present invention will readily occur to those skilled in the art to which the same relates.

I claim:

1. In combination with a scanning antenna system which includes a stationary parabolic reflector, a plurality of rotating antenna elements mounted for rotation about a point along the axis of said reflector; and a switch for controlling the transfer of energy successively to and from

said rotating antenna elements from and to said reflector thereby periodically shifting the direction of radiation of said system, said switch including a corresponding plurality of discontinuous transmission lines having a corresponding plurality of air gaps, said lines being connected to respective antenna elements through said gaps; a stationary shutter member disposed in the gap presented by the discontinuity in each of said 5 transmission lines; said shutter having an open sector permitting said transfer of energy and means for moving said transmission lines relative to said shutter member and said sector to control the transfer of energy across said gaps 10 and to scan a preselected sector of space by rotating said antenna elements with respect to said reflector.

2. A scanning antenna system including a source of radio energy, a parabolic reflector, a 20 plurality of antenna elements mounted for rotation about a point along the axis of said reflector; and a switch for controlling the transfer of energy successively to and from said rotating antenna elements from and to said reflector thereby 25 periodically shifting the direction of radiation of said system, said switch including a corresponding plurality of parallelly-connected discontinuous transmission lines having a corresponding plurality of air-gaps, each of said lines being 30 connected on one side to said source of radio energy and on the other side to a corresponding antenna element through a corresponding air-gap; a stationary disc, having a sector of predetermined size cut out of the same, said disc being 35 disposed in the gaps presented by the discontinuity in each of said transmission lines; and means for moving said transmission lines and said antenna elements relative to said disc to control the transfer of energy across said gaps to said 40 antenna elements.

3. In combination with a scanning antenna system which includes a stationary parabolic reflector, a plurality of antenna elements mounted for rotation about a point on the axis of said reflector, and a switch interposed between a source of radio energy and said antenna elements for controlling the transfer of energy successively to the 45 rotating antenna elements when they scan a predetermined angular sector with respect to said parabolic reflector, said switch comprising a corresponding plurality of pairs of coaxial transmission lines having a corresponding plurality of gaps in said lines, a stationary shutter disposed in said gaps and having an open sector whose angle 50 is equal to said predetermined angular sector, and means for simultaneously rotating all of said pairs of transmission lines and said antenna elements 55 as a unit relative to said shutter to allow the transfer of energy across said gaps only to that single antenna element whose corresponding gap 60 is within said sector.

4. A scanning antenna system including a parabolic reflector, a plurality of antenna elements mounted for rotation about a point along the 65 axis of said reflector, said antenna elements being connected to a source of radiant energy through a common concentric line and a corresponding plurality of parallelly connected concentric branch lines whereby each of said antenna elements is 70 connected to said source through said common line and a corresponding branch line, said parallelly connected concentric branch lines each having an air gap, said air gaps lying in a single plane, said air gaps normally permitting transmission of said energy through said branch lines 75

to said antenna elements, a stationary shutter disposed in said air gaps, a cut-out sector in said stationary shutter permitting transmission of said energy through the branch line positioned within said sector to the corresponding antenna element, and means for rotating said concentric branch lines and said antenna elements as a unit with respect to said stationary shutter, thereby controlling the transfer of said energy across said gaps from said source to an antenna element. 10

5. A scanning antenna system including a main stationary concentric line connected to a source of radiant energy, a plurality of rotatable concentric branch lines coupled to said main line, said branch lines each terminating in a rotatable antenna element, a stationary parabolic reflector, said branch lines and said antenna elements being mounted for rotation about a point along the axis of said reflector, said branch lines each having an air gap, said air gaps being disposed in a single plane, a stationary shutter disposed in said gaps and said plane and having a cut-away sector permitting electrical coupling between said source and said antenna elements when a corresponding concentric branch line and its air gap 25

are within said sector, a frame for mechanically integrating said branch lines and said antenna elements, and means for rotating said frame, said branch lines and said antenna elements for sequentially controlling the transfer of said energy to said antenna elements, whereby the rotation of the energized antenna element with respect to said reflector produces scanning of a preselected sector in space by said radiant energy. 5
